Des. 204,339
Patented Apr. 5, 1966

204,339

DISPLAY AND DISPENSING BOOTH

Walter R. Reach, Audubon, N.J., assignor to J & J Oven
Company, Inc., Camden, N.J., a corporation of Pennsylvania

Filed Feb. 8, 1965, Ser. No. 83,727

Term of patent 14 years

(Cl. D80—2)

The broken representation of an oven in FIGS. 1, 2, and 3 is for the purpose of illustration only.

I claim:

The ornamental design for a display and dispensing booth, as shown and described.
